UNITED STATES PATENT OFFICE.

LOUIS HENRY ZANDERS, OF SILVER CITY, IOWA.

GATE-LATCH.

No. 797,455.

Specification of Letters Patent.

Patented Aug. 15, 1905.

Application filed March 18, 1904. Serial No. 198,794.

To all whom it may concern:

Be it known that I, LOUIS HENRY ZANDERS, a citizen of the United States, residing at Silver City, in the county of Mills and State of Iowa, have invented a new and useful Gate-Latch, of which the following is a specification.

This invention relates generally to gate-latches, and more particularly to a latch adapted for use upon farm-gates, although it will be understood that the latch may be used upon any construction of gate.

Another object of the invention is to provide a latch suitable for either right or left hand gates; and the invention consists in the novel features of construction and combination, all of which will be fully described, and pointed out in the claims.

In the drawings forming a part of this specification, Figure 1 is a perspective view showing the practical application of my invention. Fig. 2 is a face view of the keeper. Fig. 3 is a perspective view of the latch. Fig. 4 is a sectional view taken centrally through the keeper, and Fig. 5 is a top plan view showing the latch in engagement with the keeper.

Referring to the drawings, A indicates an ordinary farm-gate, and B the gate-post, said gate having a latch C connected thereto and which is adapted to engage the keeper D, arranged upon the gate-post B.

The latch C consists of the vertical arm C' and the horizontal arm C², said horizontal arm having a lateral extension C³. The vertical arm is slotted vertically, as shown at C⁴, and through which screws or bolts C⁵ are passed for the purpose of securing the latch to the end batten of the gate.

The keeper comprises a horizontal arm bifurcated at one end, as shown at D', one of the members projecting beyond the other, and in practice I prefer to have this projecting member the upper one. The lower member is provided with a projection D⁵, back of which the lateral extension C³ is adapted to be guided, the bifurcation D' being of such shape as to readily guide the said extension into engagement with the projections D⁵. The keeper D is pivotally connected to a frame E, said frame being provided at its upper end with a housing E', in which the keeper is piv-

oted, and a spring F, connected to the end of the keeper, is connected also to one of the extending ends E² of the frame E. By disconnecting the spring and removing the pivot-bolt of the keeper said keeper can be reversed and the spring connected to the opposite end of the frame, thereby rendering the latch capable of use upon either left or right hand gates. In order to prevent the keeper having too great an upward movement, I employ a bar G, which is pivoted to the bottom of the frame E, as shown at G', and at its upper end is formed with a hook G², which is adapted to extend over and limit the upward movement of the keeper.

It will thus be seen that I provide an exceedingly cheap, simple, and efficient construction of reversible gate-latch.

Having thus fully described my invention, what I claim as new, and desire to secure by Letters Patent, is—

1. A device of the kind described comprising a keeper having a horizontal arm bifurcated at one end, said arm being pivoted intermediate its ends and being arranged horizontally and parallel with the inner face of the gate-post, a spring connected at one end of the non-bifurcated end of the arm, a frame having a projection, said frame being connected with the gate-post and the projection connected to the other end of the spring, and a latch adapted to be carried by a gate and having an angled laterally-projecting portion adapted to engage the bifurcated end of the keeper-arm.

2. A device of the kind described comprising a frame adapted to be secured to a gate-post and to extend upon each side of the inner face of the post, a keeper comprising an arm bifurcated at one end, said arm being pivoted to said frame and adapted to normally occupy a position parallel to the projecting portions of the frame, a bar pivoted to the frame having a hook portion, the hook portion of the bar being adapted to engage the keeper upon one side of the pivotal point, a spring adapted to be secured at one end to the non-bifurcated end of the keeper-arm and at the other end to either of the extending ends of the frame and a latch carried by a gate and adapted to engage the bifurcated end of the keeper.

3. The combination with the adjustable latch, having a lateral extension, of a reversible keeper having a bifurcated forward end, a frame to which the keeper is pivoted, a spring connecting the rear end of the keeper-arm, to the rear end of the frame, and a bar having a hook portion pivoted to the frame, and adapt-

ed to limit the upward movement of the keeper-arm.

LOUIS HENRY ZANDERS.
